SUCTION DEVICE FOR CHIMNEYS

Hermann Meuth, Stuttgart, Germany

Application January 24, 1935, Serial No. 3,315
In Germany January 30, 1934

4 Claims. (Cl. 98—71)

The invention concerns a head-piece for heating and ventilating chimneys consisting of a body with vertical slits arranged especially at the places of the highest vacuum.

5 When the wind impinges on prismatic or round bodies, a pressure and a vacuum space are produced. According to test results, the pressure space extends in the case of round bodies over $\frac{1}{6}$ th of the circumference, the remaining $\frac{5}{6}$ ths 10 act as a suction area.

Fig. 1 is the upright projection of the cylindrical head piece with a fixed covering screen surface with a diagram of vacuum space at the cover.

15 Fig. 2 is the top view of the head piece of Fig. 1 with a diagram showing the distribution of the pressure and vacuum spaces.

Fig. 3 is the upright projection of a conical head piece with movable covering screen surface 1', steered by the wind by means of the vane 8.

20 Fig. 4 is the top view of the conical head piece of Fig. 3.

Fig. 5 is the upright projection of a conical head piece tapering downwardly with apertures 25 and bars of equal width round the whole circumference.

Fig. 6 is a cross section x—x of Fig. 5.

In Fig. 1 and Fig. 2 are shown size and extent of pressure area 1 and of vacuum area 2. The 30 places of the highest vacuum are on both sides of the narrow pressure space 1, quite close to it by 3 (Fig. 2) and on the border of the cover 6 by 3' (Fig. 1).

If gases or vapours are to be drawn from hollow 35 bodies by the suction effect of the wind flowing past them, it will be advisable to cover the outlet openings 4 in the surface of the body only in the narrow area of the pressure by means of a correspondingly small imperforate surface 1 (Figs. 1 40 and 2) and to keep open the other apertures 4 for the outlet in the whole vacuum space 2 (Fig. 2), especially on the places of the highest vacuum 3 (Fig. 2) and 3' (Fig. 1, openings 1 on the border of the cover 6). For same suction effect 45 by other directions of the wind a movable surface 1' (Figs. 3 and 4) steered by the wind may be arranged. For this purpose the surface 1' (Figs. 3 and 4) is revolvable on a central pivot and counterbalanced by the vane 8. Tests have shown 50 that a particularly strong suction effect is produced in this manner and that this suction effect is only a little smaller if the covering surface 1 is not imperforated but perforated, (Figs. 1 and 2) as in Figs. 5 and 6, by slits 4 whose width is 55 approximately equal to the width of the bars 5 be-

tween. This fact is the result of the small effect of the pressure according to size and extent, in comparison with the vacuum 2 (Fig. 2) and from resistance to friction on the edges of such slits which is greater than the resistance to the wind streaming around the body. 5

In order to obtain the same suction effect by all directions of the wind it is not necessary to arrange a movable surface 1' (Figs. 3 and 4) steered by the wind instead of a fixed screening surface 1 (Figs. 1 and 2). It is only necessary, as in Figs. 5 and 6, to arrange the slits in the screening surface on the whole circumference in such a manner that the slits 4 alternate with bars 5 of equal width. Tests have proved that then 10 the same suction effect is produced for all horizontal directions of wind. 15

Having now particularly described and ascertained the nature of my said invention, and in what manner the same is to be formed, I declare 20 that what I claim is:

1. A head piece for an exhaust duct comprising 25 vertically spaced strips connected together at the top and bottom, a cover connected to the strips at the top, said strips being radially equally spaced from and circumferentially spaced about a central vertical axis for at least 300° to function as a suction area, and imperforate means radially spaced from said vertical axis, extending vertically the length of said strips from top to bottom 30 and circumferentially for 60° to function as a pressure area. 25

2. A head piece for an exhaust duct comprising 35 a casing having a cover at the top and an open bottom, said casing being circular in horizontal cross section, spaced slits in and circumferentially arranged around said casing for at least 300° to act as a suction area, and imperforate means extending vertically from the top to the bottom and circumferentially of said casing for 40 60° to act as a pressure area. 35

3. A head piece as defined in claim 2 in which the width of each of the slits within the 300° is substantially of the same width as the portion of the casing between two adjacent slits and in which also the surface of the pressure area of 60° may be provided with slits and bars of equal width as on the remaining circumference of 300° . 45

4. A head piece as defined in claim 2 including means to pivotally mount said imperforate means on said cover, a wind vane pivotally mounted on said cover and means to connect said vane to said imperforate means so that the imperforate means may be steered by the wind. 50

HERMANN MEUTH. 55
